CLAIM

The ornamental design for a bird perch for hanging in the shower, as shown and described.

DESCRIPTION

FIG. 1 is a front perspective view of the novel bird perch for hanging in the shower showing how it would be mounted on a shower door;

FIG. 2 is a partial elevation view thereof showing how it would be mounted on a shower rod;

FIG. 3 is a top plan view thereof;

FIG. 4 is a rear elevation view thereof;

FIG. 5 is a left side elevation view thereof;

FIG. 6 is a front elevation view thereof;

FIG. 7 is a right side elevation view thereof; and,

FIG. 8 is a bottom plan view.
